DESIGN FOR A COMBINED BOTTLE OPENER, CAN OPENER, AND SHOEHORN

Thomas A. Addison, New Orleans, La.

Application February 27, 1937, Serial No. 67,887

Term of patent 7 years

To all whom it may concern:

Be it known that I, Thomas A. Addison, a subject of Great Britain, residing at New Orleans, in the parish of Orleans and State of Louisiana, have invented a new, original, and ornamental Design for a Combined Bottle Opener, Can Opener, and Shoehorn, of which the following is a specification, reference being had to the accompanying drawing, forming part thereof.

Figure 1 is a view in front elevation of a combined bottle opener, can opener, and shoehorn showing my new design.

Figure 2 is a view in side elevation thereof.

Figure 3 is a top plan view.

I claim:—

The ornamental design for a combined bottle opener, can opener and shoehorn, as shown.

THOMAS A. ADDISON.
